UNITED STATES PATENT OFFICE.

FRED J. COLLINS, OF ROCKFORD, ILLINOIS.

DESIGN FOR A FLOWER-BASKET.

51,633.

Specification for Design.

Patented Jan. 1, 1918.

Application filed May 5, 1917. Serial No. 166,755. Term of patent 7 years.

To all whom it may concern:

Be it known that I, FRED J. COLLINS, a citizen of the United States, residing at Rockford, in the county of Winnebago and State of Illinois, have invented a new, original, and ornamental Design for Flower-Baskets, of which the following is a specification, reference being had to the accompanying drawing, forming part thereof.

In the drawing—

Figure 1 is a plan view of a flower basket showing my new design, the pendants or suspending chains being broken off close to the basket;

Fig. 2 is a side elevation of the basket looking at the front side thereof in its position shown in Fig. 1; and

Fig. 3 is also a side elevation of the basket but looking at the right hand side thereof in its position shown in Fig. 1.

I claim:

The ornamental design for a flower basket, as shown.

FRED J. COLLINS.
